UNITED STATES PATENT OFFICE.

GEORGE WEBB, OF WEST HARTFORD, CONNECTICUT, ASSIGNOR TO COLT'S PATENT FIRE ARMS MANUFACTURING CO., OF HARTFORD, CONNECTICUT, A CORPORATION OF CONNECTICUT.

MACHINE FOR WASHING DISHES AND OTHER ARTICLES.

Application filed December 23, 1926. Serial No. 156,568.

This invention relates to a machine of the type wherein the dishes or other articles are continuously moved by a conveyor or otherwise through the machine and wherein the 5 dishes are subjected to one or more washing operations during their said movement, and the invention is particularly applicable to a machine having two or more washing divisions in which different washing operations are performed successively.

It has heretofore been the practice to construct a machine of this type with a tank at one side of the main casing, this tank being adapted to receive and contain the main 15 body or bodies of washing liquids. Pump mechanism has been provided for withdrawing the liquid or liquids from the tank and forcing them through suitable spray devices onto the dishes or other articles being 20 washed, the said liquids falling onto a suitable guide or guides which direct them laterally back into the tank. One of the objects of the invention is to provide an improved system of devices for maintaining the bodies 25 of liquids in two or more washing divisions at the proper temperatures and for compensating for wastage from the said bodies.

It has heretofore been the practice in certain machines of the present type to provide a foot lever for controlling the means 30 through which power is supplied to drive the conveyor, the foot lever being held in depressed position to cause the operation of the conveyor and the conveyor being stopped 35 when the foot lever is released. Another object of the present invention is to provide automatically acting means for holding the foot lever in its depressed position so that the continued pressure of the operator's foot 40 is not needed to maintain the conveyor in operation.

A further object of the invention is to provide a conveyor belt supporting track having certain improved details of construction and 45 mounting, and to provide other improved features of construction for supporting and driving the conveyor belt.

Further objects of the invention will be 50 apparent from the following specification and claim.

In the accompanying drawings forming a part of this specification, I have shown the embodiment of the invention which I

now deem preferable, but it will be understood that the drawings are intended for illustrative purposes only and are not to be construed as defining or limiting the scope of the invention, the claims forming a part of this specification being relied upon for that purpose.

Of the drawings:

Figure 1 is a right side view of a dish washing machine embodying the invention.

Fig. 2 is a left side view of the machine.

Fig. 3 is a transverse sectional view taken 65 along the line 3-3 of Fig. 2.

Fig. 4 is a fragmentary end view showing the liquid containing tank and the supply pipes therefor.

Fig. 5 is a detail view, partly in section, of 70 the supplemental heater for the third washing division.

Fig. 6 is an enlarged fragmentary perspective view of the clutch and valve mechanisms.

Fig. 7 is a fragmentary perspective view 75 of the treadle and associated parts.

Fig. 8 is a fragmentary perspective view 80 of one of the supporting drums for the conveyor belt.

Fig. 9 is a side view, partly in section, showing a part of the conveyor belt and a part of one of the supporting drums therefor.

Fig. 10 is an enlarged fragmentary plan 85 view of the conveyor belt.

Fig. 11 is a plan view on a still larger scale, showing one unit of the conveyor belt.

Fig. 12 is a plan view, on the same scale 90 as Fig. 10, showing another unit of the conveyor belt.

Figs. 13 and 14 are plan views on the same scale as Fig. 10, showing still other units of the conveyor belt.

Fig. 15 is an enlarged fragmentary sectional view taken along the line 15-15 of 95 Fig. 10.

Referring to the drawings, 1 represents the main casing of the machine, this casing being generally rectangular in cross section 100 as shown in Fig. 3, and being provided with side walls 2 and 3, with a top wall 4 and a bottom wall 5. The ends of the casing are open, at least in part, to permit the dishes or other articles to be washed to be introduced at one end and to permit the washed

dishes or other articles to be removed at the other end. Flexible curtains 1^a, 1^a may be provided to prevent liquid from splashing out of the open ends of the casing.

5 The casing 1 is supported in a relatively elevated position by a suitable framework 6, this framework 6 as shown being constructed from structural steel parts. The framework includes four vertical members 10 7, 7 and 8, 8 located at the respective corners of the casing and extending downward to form main supporting legs for the machine. At each side of the machine are longitudinal members 9, 9 and 10, 10 connecting the respective uprights 7, 7 and 8, 8. Suitable transverse members such as 11 serve to connect the said uprights and the said horizontal members. Preferably, for a purpose to be presently described, an additional longitudinal member 12 is located between the members 10, 10 and connected at its ends with the transverse members 11. If desired, additional uprights 13, 13 may be provided between the uprights 7, 7 and 8, 8 these uprights 13, 13 providing additional legs for supporting the machine.

Means is provided for moving the dishes to be washed through the casing 1 from end to end thereof and as concerns some of the 30 features of the invention, this moving means can be varied within wide limits. Preferably, however, and in accordance with other features of the invention, the means for moving the articles comprises an endless open- 35 work conveyor which extends through the casing substantially from end to end thereof and which is adapted to have the dishes or other articles placed directly upon it. The endless belt of the conveyor is represented in 40 the drawings at 14, this belt being supported at the ends of the machine by means of rollers or drums 15 and 16, one of which serves for driving the belt, as will hereinafter be described in detail. The conveyor is operated 45 in the direction of the arrow shown in Fig. 1, the dishes being placed upon the belt at the left hand end of the machine and being discharged therefrom at the right hand end of the machine.

50 A tank 17 is provided for containing a supply of cleansing liquid, this tank being at one side of the casing 1 and at one side of the path of the articles through the said casing and below the level of the said path. 55 Preferably, the tank 17 is carried by the main frame work which has already been described and for this purpose the frame work is provided with transverse members 18, 18 which are secured to the main longitudinal members 9 and 10.

In accordance with the preferred form of the invention, the machine comprises a plurality of washing divisions through which the articles are moved successively and in which they are subjected to different

washing operations. The number of divisions may be varied but for purposes of illustration, I have shown three such divisions. Each division comprises a set of spray devices, a receptacle for a body of washing liquid, means for withdrawing the liquid from the receptacle and delivering it to the spray devices which discharge it against the articles in the said division, and means for automatically returning the liquid to the receptacle from which it was withdrawn, thus maintaining a continuous cycle of movement.

When the machine is provided with three washing divisions, the three receptacles for the respective divisions are preferably formed by providing transverse partitions 19 and 20 in the tank 17, these partitions dividing the tank into three receptacles or compartments 21, 22 and 23. Pump means 85 are provided for withdrawing the liquids from the respective receptacles and for this purpose, I prefer to provide a device having a single pump casing 24 with separate chambers therein. The pump device is preferably located directly beneath the casing 1 and at one side of the tank 17. The pump device is shown as comprising a longitudinally extending horizontal main shaft 25 on which there are three separate impellers 26, 27 and 28 located respectively in independent pump chambers 29, 30 and 31. A suitable drive means, such as an electric motor 32, is provided for operating the pump. The pump device and the motor 32 are shown as supported upon a base plate 33 carried by the frame members 10 and 12. The suction sides of the pump chambers 29, 30 and 31 are connected respectively by means of pipes 34, 35 and 36 with the respective receptacles or tank compartments 21, 22 and 23. Preferably, in each tank is a strainer 37 which serves to prevent refuse and the like from entering the corresponding pipe 34, 35 or 36.

100 The details of the spray devices in the respective washing divisions can be varied but I prefer to provide and have shown two horizontal spray pipes 38 and 39 in each division extending transversely across the casing and located respectively above and below the upper run of the conveyor 14. The said spray pipes 38 and 39 are provided with holes located respectively in the lower and upper parts thereof so that the said spray pipes serve to deliver the washing liquid in opposite directions against the articles on the conveyor 14. The washing liquid is supplied to the spray pipes in the respective divisions by means of supply pipes 105 40, 41 and 42, which are connected respectively with the discharge sides of the pump chambers 29, 30 and 31.

110 Preferably I provide an inspection opening in the side wall of the casing adjacent 130

each pair or group of spray pipes 38 and 39. When there are three groups of spray devices as shown there are provided three separate inspection openings 40^a, 41^a and 42^a longitudinally spaced in accordance with the longitudinal spacing of the said spray pipes. The said openings 40^a, 41^a and 42^a are normally closed by means of doors 40^b, 41^b and 42^b these doors being independently openable to permit inspection of one group of spray devices independently of the others. I do not necessarily limit myself as concerns the construction and mounting of the said doors 40^b, 41^b and 42^b but I have shown them as being vertically slidable.

In order that the liquid discharged from the spray pipes in the respective divisions may be returned as already described, to the corresponding receptacle or tank compartment, the main casing 1 is provided at its side with liquid discharge openings 43, 43 corresponding in number to the number of divisions and tank compartments. These openings are so located that the liquids discharged from them will pass directly into the corresponding receptacles or tank compartments 21, 22 and 23. Preferably, and as shown, the bottoms of the discharge openings are adjacent the bottom wall 5 of the casing, thus making it possible for any liquids on the said bottom wall to pass out through the discharge openings into the corresponding tank compartments. As shown there is provided at each of the discharge openings 43, 43, a spout or chute 44, which projects outward over the corresponding receptacle. This serves to prevent any liquids from entering any opening which might extend between the casing and the tank.

Preferably, I provide for each division a laterally inclined guide plate 45 for receiving and guiding laterally at least a portion of the liquid discharged from the corresponding spray devices. When the main casing 1 is provided with a continuous integral bottom wall 5 as shown, the removable guide plates are located above the said bottom wall and preferably also above the lower run of the conveyor, as indicated in Fig. 3. Each plate is so located that the liquids received upon it are discharged laterally through the corresponding discharge opening in the side wall of the casing and into the corresponding tank compartment. Each guide plate 45 is made removable, thus making it possible for the plate itself to be easily cleaned and further making it possible for access to be conveniently had to the portions of the conveyor and of the bottom wall 5 located below the guide plate.

I prefer to so construct and locate the guide plate 45 that it can be removed laterally through the corresponding discharge opening 43 as shown in Fig. 3. The main body of the plate 45 is inclined in order to

guide the liquid laterally as described, but preferably the sides of the plate are extended upward to form horizontal supports or guides which enable the plate to be removed in a horizontal direction, the plate 70 passing through the position shown by dotted lines.

Preferably, in addition to the three guide plates 45, 45, beneath the respective spray devices, I provide other parts which, together with the said guide plates, constitute a shield extending, as an entirety, throughout the greater part of the length of the casing. The shield comprises in each division longitudinally inclined sections 47, 47 which are formed at their edges with flanges for engaging the horizontal supports or guides 46, 46 on the corresponding guide plate. Stops 45^a are provided for engaging the corresponding shield sections 47 to limit inward movement of each guide plate. It will be apparent that the shield as an entirety serves to receive the greater part of the liquid discharged from the several spray devices and to direct it onto the respective 85 guide plates which serve to guide it laterally outward through the discharge openings in the casing and into the tank compartments. Any liquid which may not be caught by the shield or which may escape at the edges of the guide plates 45, 45 is caught by the bottom wall 5 of the casing.

Preferably in order to reduce to a minimum the mixing of the separate bodies of liquid as they pass through the casing, partitions or guards are provided. Mounted upon the shield are two upward extending guards 48, 48, these partitions registering, or approximately registering, with the partitions 19 and 20 in the tank. Projecting 105 downward from the top of the casing are two sets of guarding means. As shown, each set of such means comprises a central partition 49 located directly above the corresponding partition 48 and it also comprises two other guard partitions 50, 50 which serve to catch some of the splash and to further prevent mixing of the liquids.

In order to prevent as far as possible any scrap or refuse from passing with the washing liquids into the lower parts of the compartments, the said compartments are provided respectively with screens 51, 51, which extend across the upper parts of the said compartments and which are located in the 115 paths of the liquids discharged thereinto. The said screens are freely removable separately from the respective compartments in order that the screens may be cleaned when necessary and in order further that 120 the interiors of the compartments may be inspected. In order to prevent splash and for other purposes, the tank 17 is normally covered, the covering means comprising at least in part openable doors 52, 52 located 130

above the respective screens 51, 51. The doors are inclined as clearly shown in Fig. 3 and they are so located that the opening of the door not only provides access to the interior of the corresponding compartment, but also provides access to the corresponding discharge opening in the casing and permits the corresponding guide plate to be removed from the machine as shown in Fig. 3. The doors are shown as hinged at their upper edges. It will be seen that inasmuch as I have provided separate tank doors, one for each division, it is possible by opening the proper door to inspect any one of the compartments and remove the screen therefrom if necessary, without opening any other compartment and permitting liquid to be splashed out of the machine. Furthermore, by opening any one door, it is possible to remove the corresponding guide plate 45 without the splashing and other disadvantages incident to the opening of the other doors.

A system of piping is provided for introducing water into the several compartments to initially fill them or to replenish losses. These same pipes may also be used for introducing steam to initially heat the liquids in the respective compartments or to auxiliary maintain the heat thereof when necessary. As illustrated, there are pipes 53, 54 and 55 communicating with the respective compartments 21, 22 and 23, the said pipes being provided respectively with valves 56, 57 and 58. As shown in Fig. 4, the said pipes connect with a manifold 59 and with the manifold are connected two pipes 60 and 61 provided respectively with valves 62 and 63. One of the said pipes is connected with a water supply and the other with a steam supply. It will be obvious that by properly manipulating the valves 56, 57, 58, 62 and 63, either water or steam or both may be admitted as required to any of the tank compartments.

In order to control the level of the liquids in the several compartments overflow pipes 64, 64 are provided in the respective compartments, these pipes communicating with a main discharge pipe 65. Thus the level of the liquid in any compartment is prevented from rising above the top of the corresponding pipe. Each pipe is seated in a sleeve 66 having an opening 67 therein. By raising any one of the pipes the liquid may be permitted to drain out of the corresponding compartment. The first compartment 21 is preferably also provided with an overflow slot 68 which communicates with a pipe 69 leading into the main discharge pipe 65. Adjacent the slot 68 there is a removable screen 70 through which liquid must pass before entering the pipe 69. The level of the slot 68 is somewhat below the level of the top of the corresponding pipe

64 and the normal overflow from the compartment 21 is therefore through the slot 68, thus causing the grease and floating refuse to pass through the slot 68 and through the screen 70 instead of passing directly into the main discharge pipe through the overflow pipe 64.

In the operation of the machine, a body of liquid is maintained in the first division, which liquid contains a suitable detergent and is maintained at a proper moderately low temperature. This liquid is continuously circulated and sprayed against the dishes or other articles as already described. The body of liquid in the second division is preferably maintained at a much higher temperature than that in the first division and this liquid may also, if desired, contain a suitable amount of detergent. This liquid is similarly circulated and sprayed against the dishes or other articles. The liquid in the third division is substantially clean water which is kept at or near the boiling point. This liquid is similarly circulated and sprayed against the dishes or other articles. Preferably, in addition to subjecting the dishes or other articles to the action of the three bodies of washing liquid as described, I also subject them to a final rinsing spray. For this purpose, I have shown a plurality of rinsing nozzles 71, 71 and 72, 72 located respectively above and below the path of the dishes, these nozzles being connected with a supply pipe 73. The rinse water delivered through the nozzles 71, 71 and 72, 72 is at or near the boiling temperature in order that it may serve, not only to rinse the dishes but also, to sterilize them and heat them to facilitate drying. The rinse water falls onto the shield which has been described and is caused by the corresponding guide plate 45 to pass into the tank compartment 23 containing the clean or substantially clean hot water as already described. This rinse water added to the body of water in the compartment 23 assists in heating the said body of water and may in some cases heat it sufficiently to avoid the necessity for any other heating by means of steam introduced by means of the pipe 55.

For heating the water delivered to the rinse spray nozzles through the pipe 73, I preferably provide a steam operated heater 74 which may be of any usual or preferred form. I have shown a heater which comprises a cylinder within which is contained a coiled pipe 75 connected at one end with the rinse water pipe 73 and at the other end with a water supply pipe 76. Steam is supplied to the interior of the cylinder so as to surround the coil 75, a pipe 77 being shown for this purpose. The water is thus heated to approximately the temperature of the steam as it passes through the said coil

75. The exhaust steam and the water of condensation from the heater 74 pass through a pipe 78 into the compartment 22 of the second washing division and serve two purposes, first to heat the liquid in the said compartment and second to increase the volume thereof and compensate for losses and wastage.

10 The maintenance of the proper temperature of the liquid in the first washing division is very important. This liquid requires a considerable amount of heating for the reason that there is a tendency for it to be rapidly cooled by coming into contact 15 with the freshly introduced cold dishes, but suitable provision must be made to prevent the water being heated beyond a proper predetermined temperature as the use of too hot liquid for the initial washing tends to 20 bake certain materials upon the dishes instead of removing the said materials. In order that the temperature of the liquid in the first division may be properly controlled, I prefer to provide a thermostatically 25 controlled heating means.

As shown and as preferred, steam is supplied to the interior of the compartment 21 through a pipe 79 and the flow of steam through this pipe is regulated by means of 30 a valve 80. Projecting into the compartment 21 is a suitable thermostatic device 81, this device being connected with the valve 80 by means of a flexible pipe 82. The thermostatic device 81 does not of itself 35 form any part of the invention and any of the well known devices adapted for this purpose may be used. The device shown operates through a column of liquid contained in the pipe 82 and acting upon the 40 valve 80. A guard 83 within the compartment and a guard 84 outside thereof protect the thermostatic device from mechanical injury. When the temperature in the compartment 21 reaches a predetermined 45 point, the valve 80 is automatically closed and when the temperature falls below a predetermined point, the valve 80 is automatically opened. In practice, the valve is ordinarily maintained in a partly open position so as to permit a continuous flow of 50 steam just sufficient to compensate for the heat losses in the liquid due primarily to its coming into contact with the cold dishes. Because of the considerable amount of heating required, the condensed steam which is 55 added to the liquid is ordinarily sufficient to maintain the required volume of the liquid and compensate for wastage.

As already stated, the water in the third 60 division is primarily heated by the addition thereto of the hot rinse water. In some cases this may not be sufficient and it may be necessary to auxiliarly heat the water by means of steam introduced through the pipe 65 55. Preferably, I provide a thermostatic de-

vice for controlling the flow of steam so as to maintain the water at the required temperature. A suitable device for this purpose is indicated at 85 in Fig. 1 and is shown in greater detail in Fig. 5. Carried by the 70 pipe 55 is a small open sided body having a valve seat at 86. Within the body is a device 87 which includes an element adapted to expand and contract in accordance with temperature variations, this element carrying a valve closure 88 cooperating with the seat 86. When the water is at a proper temperature the valve closure 88 is held against the seat 86, but when the temperature falls the valve closure is withdrawn from the seat 80 and steam is admitted.

Under some circumstances, the condensed steam from the heater 74 is not sufficient to maintain the required volume of liquid in the second compartment 22. In order to 85 supply additional liquid to the said compartment, I may use and have shown a transfer pipe 89 which discharges into the said compartment 22. The pipe 89 is connected at its other end with a small basin 90 which is 90 secured to the bottom wall 5 of the main casing, the said basin being provided with one or more holes communicating with the casing. It will be understood that the guide plates, such as 46, do not closely engage the 95 adjacent sections of the shield and that there is considerable leakage past the edges of the said guide plates and otherwise onto the said bottom wall 5. A certain amount of this leakage enters the basin 90 and thence passes 100 into the compartment 22. The overflow may not be large but only a small amount is required to maintain the liquid in the compartment 22 at the proper level.

The mechanism for driving the conveyor 105 preferably receives its power from the pump shaft 25 already described. Directly coupled to the pump shaft 25 is a conveyor drive shaft 91 upon which is mounted a worm 92 meshing with a worm wheel 93 on a transverse shaft 94. Mounted in alignment with the transverse shaft 94 is a second transverse shaft 95, and these two shafts are connectible by means of a clutch 96, this clutch being shown as of the positively acting jaw type. 115 The clutch comprises a toothed member 97 secured to the shaft 95 and a companion toothed member 98 splined on the shaft 94 and operable by means of a bell-crank 99. At the end of the shaft 95 is a sprocket 120 wheel 100 and a chain 101 passes around this sprocket wheel and around another sprocket wheel 101* on an idler shaft 102. The said shaft 102 carries a second smaller sprocket 103 around which passes a chain 104, the said 125 chain also passing around a sprocket 105 secured to the shaft 106 on which the conveyor drum 15 is mounted.

For controlling the starting and stopping of the conveyor, I preferably use a mecha- 130

nism similar in many respects to that disclosed in the patent of Elbert L. Couch, No. 1,640,693 issued August 30, 1927. For operating the clutch 96, there is provided a lever 107 which engages one arm of the bell crank lever 99. The outer end of the lever 107 is connected by means of a link 108 with a lever 109 on a transverse rock shaft 110, shown most clearly in Fig. 7. Carried by the rock shaft 110 is a foot treadle 111, this treadle being in position to be within convenient reach of the operator who is engaged in removing the dishes as they are delivered from the machine. An adjustable stop 111^a is provided for the treadle 111. It will be seen that when the treadle is moved downward, the lever 107 is moved in the clockwise direction, thus moving the bell crank lever 99 in the clockwise direction as viewed in Fig. 6 and engaging the clutch 96. A spring 112 tends to move the lever 107 in the counterclockwise direction, thus disengaging the clutch when the treadle 111 is released and permitted to move upward.

Preferably and in accordance with the invention, I provide a latch 113 which operates by gravity to automatically engage the treadle 111 and hold it in its lower position. The latch is so positioned that the operator can easily engage it with his foot so as to move it backward and release the treadle, thus permitting the clutch to be disengaged. It will be seen that the provision of the latch obviates the necessity of the operator keeping his foot continuously upon the treadle as has been necessary in accordance with prior practice. At the same time, it makes it possible for the operator to easily and quickly stop the machine by a simple foot motion, that is, by releasing the latch and permitting the treadle to rise.

A shelf 115 is provided adjacent the delivery end of the conveyor, this shelf serving to guide dishes from the conveyor onto a table (not shown). The shelf is pivoted for movement about a transverse axis at 116 and it is normally held in position adjacent the conveyor by means of springs 117, 117. The link 108 is not directly connected with the lever 107 but is connected therewith by means of a latch 118 which is pivoted to the lever and which engages a shoulder on the link at 119. One of the arms carrying the shelf 115 is provided with an extension 120 carrying a transverse stud 121 which engages the latch 118. The construction is such that when the shelf is moved outward, the latch 118 is disengaged from the shoulder 119, thus permitting the lever 107 to move under the influence of the spring 112 and to disengage the clutch and stop the conveyor. The construction described serves as a safety mechanism to prevent injury to the machine or to the operator in case a broken dish or anything

else becomes jammed between the conveyor and the shelf. It will be seen that when the shelf 115 has been moved and the latch 118 disengaged, re-engagement of the latch is impossible until the shelf obstruction has been removed and the shelf has been returned to its normal position by means of the springs 117. It will further be observed that the return of the shelf to normal position will not start the machine. The starting of the conveyor can be effected only by raising the treadle and correspondingly lowering the link 108 so as to permit the latch 118 to engage the shoulder 119.

Preferably, as shown most clearly in Fig. 6, a valve 73^a is provided for controlling the flow of rinse water through the pipe 73. This valve is so constructed that it tends to close itself, and it is provided with a stem 73^b by means of which it may be opened and held open. For moving the valve stem 73^b, a lever 107^a is provided arranged to be operated by the lever 107. When the inner end of the lever 107 is moved downward to move the bell-crank 99 and engage the clutch 96, the lever 107^a is moved in the clockwise direction to open the valve 73^a. When the lever 107 is moved in the opposite direction to release the clutch, the valve 73^a is permitted to close.

The conveyor belt and the mounting therefore as shown in detail in Figs. 8 to 15 are not claimed as a part of the present invention, these being set forth and claimed in my copending application for link belt conveyor, Serial No. 199,089 filed June 15, 1927 as a division of this present application. The said conveyor belt comprises a series of articulated links or units, one of which is shown in detail in Fig. 11. At each side of each unit are two similar metallic plates 122 and 123 and between these two plates there is held a sheet or plate 124 of relatively soft non-metallic material, such as fiber. The two pairs of plates at each side of the unit are connected at each end by means of a tube 125 which is riveted over at its ends to hold the plates and to thus connect the parts of the unit.

In assembling the chain belt, the several main units are arranged as shown in Fig. 10 and they are pivotally connected together by means of tubes or bushings 126, 126 which extend transversely throughout substantially the entire width of the belt.

Preferably, rollers 127, 127 are provided at the edges of the chain for supporting it on suitable rails or guideways in the washing machine. For mounting the rollers, special links or units are provided as shown in detail in Fig. 12. Each unit comprises a sheet metal plate 128 having two bushings 129, 129 riveted thereto, these bushings preferably being the same in diameter as the two bushings 125, 125 and being sim-

ilarly spaced. As indicated by dotted lines in Fig. 12, a roller 129 is mounted on one of these bushings.

In addition to the units already described, 5 there are auxiliary connecting links 130, 130 and 131, 131 as shown in detail in Figs. 13 and 14 respectively. Each link 130 has two inward extending bushings 130^a, 130^a of the same diameter as the tubes 126. Similarly 10 each link 131 has two outward extending bushings 131^a, 131^a also of the same diameter as the tubes 126.

The several units and links are assembled in the relation shown in Fig. 10, the bushings 130^a and 131^a extending into the corresponding larger bushings 129 of the roller units. In order to tie together all of the parts of the chain belt and to prevent the said parts from moving longitudinally of 15 the tubes 126, 126, I provide tie rods 132, 132, which extend through the said tubes 126, 126 respectively and through the corresponding bushings 130^a and 131^a. The said tie rods are provided with removable 20 means at the ends such as nuts 133, 133 for holding the said rods in place. It will be obvious that by removing the nuts the entire chain belt or any part thereof may be 25 disassembled to permit the repair or replacement of parts.

The drum 15 at the driving end is provided at each end with a head in the form of a sprocket wheel 134. This wheel is provided with projections 135, 135 having 30 notches for receiving the bushings 129, 129 between the rollers 127, 127. Each sprocket wheel is also provided with recesses 136, 136 to receive the rollers 127, 127, ample clearance being provided so that the rollers 40 are free, thus permitting the chain links or units to directly engage the drum. The drum 16 at the other end is provided with a head at each end similar to those for the drum 15, but without the notched projections 45 135, 135.

The rails for engaging the rollers 127, 127 and for thus supporting the upper run of the chain are indicated at 137, 137 in the drawings. These rails extend substantially 50 the entire distance between the drums 15 and 16 and are shown as being in the form of angle irons. They are preferably removably supported in the main casing 1 by means of brackets 138, 138 and each of them 55 is held against longitudinal movement by means of pins 139 (shown in Fig. 2) extending outward from the vertical portion of the rail and into suitable apertures in the corresponding bracket. Preferably, in addition to the rails 137, 137 for supporting the 60 upper run of the conveyor, I provide other similar rails 140, 140 for supporting the lower run thereof. These rails 140, 140 are similar to the rails 137, 137 and are similarly supported.

Preferably, the lower horizontal section of each rail 139 or 140 is provided with an aperture or interruption therein at or near the point of separation between the respective washing divisions. As shown, each upper 70 rail 137 is cut away at 141, 141, the portions of the horizontal section adjacent the interruption being turned downward. It will be noted that each interruption 141 is in register with the corresponding dividing 75 partition 48 and that any drip from the turned down portion will remain on the corresponding side of the partition. The purpose of the interruption is to prevent liquid from one washing division from flowing 80 along the horizontal rail section, perhaps aided in such flow by the travel of the conveyor, and passing into the next adjacent washing division. The interruptions in the rail serve to prevent this transfer of liquid 85 from one washing division to another. The lower rails 140, 140 may be provided with similar interruptions 142, 142 and auxiliary dividing partitions 143, 143 may be provided in register with the said interruptions. 90

What I claim is:

1. In a machine for washing dishes or other articles, the combination of a main casing open at its ends and partly open at one side, means for moving through the casing from end to end thereof the articles to be washed, a tank at one side of the casing and of the path of the articles therethrough and below the level of the said path, the said tank having a plurality of compartments arranged in a longitudinal row and each adapted for containing a supply of cleansing liquid, a plurality of separate independent doors covering the respective compartments of the tank and also covering the side opening of the 100 casing, means for withdrawing the liquids from the respective compartments and delivering them separately against the articles being moved through the casing by the said moving means, and a plurality of guide plates 105 within the casing below the path of the articles and arranged to receive respectively the liquids separately delivered as aforesaid and falling from the said articles and from the moving means therefor, the said plates normally serving to separately guide the said liquids laterally into the respective tank compartments and the said plates registering with the respective doors and each being freely removable independently of each 110 other laterally through the open side of the casing when the registering separate door is open.

2. In a machine for washing dishes or other articles and comprising a plurality of washing divisions, the combination of means for moving the articles to be washed successively through the said divisions, a plurality of receptacles in the respective divisions for containing separate bodies of washing 125 130

liquids, means for withdrawing the liquids from the respective receptacles and delivering them separately against the articles being moved through the divisions by the said moving means, the said liquids automatically returning to the respective receptacles from which they are withdrawn, means for delivering hot rinse water against the articles in the last division, the said rinse water flowing into the receptacle in the said division and serving to heat the main body of liquid therein, a steam operated heater for the rinse water through which the said water flows to the delivering means therefor, and means for conducting the exhaust steam and water of condensation from the heater to one of the other receptacles to heat the main body of liquid therein.

3. In a machine for washing dishes or other articles and comprising three washing divisions, the combination of means for moving the articles to be washed successively through the said divisions, three receptacles in the respective divisions for containing separate bodies of washing liquids, means for withdrawing the liquids from the respective receptacles and delivering them separately against the articles being moved through the divisions by the said moving means, the said liquids automatically returning to the respective receptacles from which they are withdrawn, means for delivering hot rinse water against the articles in the third division, the said rinse water flowing into the receptacle in the said division and serving to heat the main body of liquid therein, a steam operated heater for the rinse water through which the said water flows to the delivering means therefor, means for conducting the exhaust steam and water of condensation from the heater to the receptacle in the second division to heat the main body of liquid therein, and thermostatically controlled means independent of the said heater for heating the liquid in the receptacle in the first division.

4. In a machine for washing dishes or other articles and comprising three washing divisions, the combination of means for moving the articles to be washed successively through the said divisions, three receptacles in the respective divisions for containing separate bodies of washing liquids, means for withdrawing the liquids from the respective receptacles and delivering them separately against the articles being moved through the divisions by the said moving means, the said liquids automatically returning to the respective receptacles from which they are withdrawn, means for delivering hot rinse water against the articles in the third division, the said rinse water flowing into the receptacle in the said division and serving to heat the main body of liquid therein, a steam operated heater for the rinse water through

which the said water flows to the delivering means therefor, means for conducting the exhaust steam and water of condensation from the heater to the receptacle in the second division to heat the main body of liquid therein, means supplemental to the rinse water for auxiliarily heating the liquid in the receptacle in the third division, and thermostatically controlled means independent of the said heater for heating the liquid in the receptacle in the first division.

5. In a machine for washing dishes or other articles, the combination of an endless openwork conveyor for carrying through the machine the articles to be washed, means for driving the conveyor, means for washing the said articles while being moved by the conveyor, a foot treadle near the floor at the delivery end of the conveyor in position to be engaged by the foot of an operator engaged in removing the washed articles from the machine, the said treadle being movable downward to render the driving means operative and upward to render the said means inoperative, and an automatically engaging latch for holding the treadle in its lower position, the said latch being releasable by the operator's foot to permit the treadle to move upward.

6. In a machine for washing dishes or other articles, the combination of an endless openwork conveyor for carrying through the machine the articles to be washed, means for driving the conveyor, means for washing the said articles while being moved by the conveyor, means for starting and stopping the conveyor, a shelf movable relatively to the conveyor and serving to receive the washed articles therefrom, a foot treadle near the floor at the delivery end of the conveyor in position to be engaged by the foot of an operator engaged in removing the washed articles from the said shelf, a connecting means between the treadle and the starting and stopping means including a releasable latch, the said connecting means serving to render the driving means operative upon downward movement of the treadle and serving to render the said means inoperative upon upward movement of the treadle, an automatically engaging latch for holding the treadle in its lower position, the said latch being releasable by the operator's foot to permit the treadle to move upward, and means controlled by the movement of the said shelf in the direction of travel of the conveyor for releasing the first said latch and thereby operating the starting and stopping means to stop the conveyor while the second said latch remains in engaged position.

7. In a machine for washing dishes or other articles and comprising a plurality of washing divisions, the combination of an open ended casing, means for washing the

said articles within the casing, an endless openwork conveyor for moving the articles to be washed successively through the said divisions, the said conveyor comprising a chain belt having two series of supporting rollers at the respective sides thereof, and two rails at the sides of the casing for en-

gaging the rollers of the respective series and for supporting the belt, each rail having an opening in the rail engaging surface thereof to prevent liquid from flowing along the said surface from one division to another.

GEORGE WEBB.
